COFFEE MAKER OR SIMILAR ARTICLE

Enrico Radaelli, Milan, Italy

Application June 3, 1953, Serial No. 25,308

Term of patent 3½ years

(Cl. D44—26)

To all whom it may concern:

Be it known that I, Enrico Radaelli, a citizen of Italy, residing at Milan, Italy, have invented a new, original, and ornamental Design for a Coffee Maker or Similar Article, of which the following is a specification, reference being had to the accompanying drawings forming part thereof.

In the drawings:

Fig. 1 is a side elevational view of a coffee maker or similar article showing my new design;
Fig. 2 is a top plan view thereof; and

Fig. 3 is a perspective view thereof.

I claim:

The ornamental design for a coffee maker or similar article, substantially as shown.
